UNITED STATES PATENT OFFICE

WILLIAM ELSTUN, OF THOMPSONVILLE, ILLINOIS.

TRUSS.

SPECIFICATION forming part of Letters Patent No. 373,927, dated November 29, 1887.

Application filed July 20, 1887. Serial No. 245,614. (No model.)

To all whom it may concern:

Be it known that I, WILLIAM ELSTUN, of Thompsonville, in the county of Franklin and State of Illinois, have invented a certain new and useful Improvement in Trusses; and I do hereby declare the following to be a full, clear, and exact description of the invention, such as will enable others skilled in the art to which it appertains to make and use the same.

10 My invention relates to an improvement in trusses.

The object is to provide a supporting-bar which shall be capable of a ready adjustment, and which will keep its position perfectly on the body under all forced movements of the muscles, which will afford an extended bearing for the pad-supporting studs and clips, and which will present rounded edges toward the body.

20 A further object is to provide a spring in connection with the pads and their supporting-studs which will admit of a free yielding movement of the pads and at the same time prevent the disagreeable grating sound so common to many of the trusses in common use.

25 With these ends in view my invention consists in certain features of construction and combinations of parts, as will be hereinafter described, and pointed out in the claims.

30 In the accompanying drawings, Figure 1 is a view of the truss in perspective. Fig. 2 is a partial horizontal section through the axes of the pad-supporting studs and the spring; and Fig. 3 is a vertical section taken transversely 35 through the supporting-bar, stud, spring, and pad.

A represents the supporting-bar. It is made of the best spring-steel, is flat, and has its upper and lower edges rounded, as shown.

40 It is preferably formed by rolling out a round rod of steel, thereby giving the rod two opposite flat faces. It is intended that the rod shall be rolled to such a thickness as to cause it to retain the necessary amount of spring force to 45 hold itself in position on the body after being sprung thereon and yet not have unnecessary weight nor be so stiff as to prevent the free action of the body-muscles. Its flat faces at the front a are about parallel with the surface

50 of the body opposite which it is intended to be placed, while over the hips, as at a', its upper

edge is turned slightly inward, and at its ends a², which rest against the back, its lower edge is slightly advanced toward the body, which slight twist, taken in connection with the edge-wise curve of the bar over the hips, serves to prevent any tendency to displacement, whether the ends be connected by a strap or not. The bar is covered with a soft-leather sheath, B, extending from the extremities of its ends to 60 points near the pad-supporting studs at the front.

C represents the pad-supporting studs, provided on their ends toward the supporting-bar with flat heads c, and their opposite ends 65 are preferably upset, as shown at c', after the stud has been passed through the back plate, D, of the pad.

E represents one of the pads, preferably made of some light soft wood and of the usual 70 form. It has a recess, e, in its back, intended to be deep enough to allow the desired play of the pad toward and away from the supporting-bar, and of sufficient diameter to freely admit the upset end of the pad-supporting 75 stud and at the same time allow the pad the desired amount of lateral tilting or rocking movement to render it easy under the various movements of the body.

The back plate, D, above referred to, is a 80 thin metallic plate and covers the mouth of the recess e. It is provided with a perforation, d, through which the shank of the stud closely passes, and is preferably, though not necessarily, provided with rounded raised portion 85 d', immediately around the perforation d, to form a bearing for the free end of the spring F, as will hereinafter appear.

The pads E are held in normal adjustment at the limit of their movement away from the 90 supporting-bar by means of a flat bow-shaped spring, F, which is secured centrally to the supporting-bar, midway between the pads, by a clip, G, provided with a set-screw, g. The clip is of the ordinary form employed in securing 95 the stud-heads to the supporting-bar, and similar clips are herein shown in connection with the pad-supporting studs to secure them to the supporting-bar.

The free ends of the spring F are provided 100 with elongated slots f, adapted to loosely receive the shanks of the studs C. The slots f

may be closed, as shown, in which case the stud would be passed through before having its end upset; or the slot might be formed open at the end and the spring adjusted after the 5 studs are in place.

When the back plates, D, are provided with the rounded raised portions d', the ends of the spring which rest thereon are made slightly concave in cross-section, as shown, the concave face of the spring being arranged to rest in contact with the convex face of the raised portion d', whereby the pad is allowed an easy rocking movement under the tension of the spring. The elongated slot f admits of the 15 adjustment of the pad supporting stud at different points along the supporting-bar to suit the requirements of different cases. The extreme ends of the spring are rolled back, as shown at f', to prevent it from chafing the 20 clothing. As thus constructed, the pad is allowed a uniform yielding motion free from the catching and grating sound which at times is found to be annoying in cases where the well-known spiral spring is employed.

25 It is evident that other means than upsetting the end of the stud C might be resorted to to secure it in the recess below the back plate—such, for example, as passing a pin transversely through its ends—and that other slight 30 changes in the form and arrangement of the several parts might be resorted to without departing from the spirit and scope of my invention; hence I do not wish to limit myself strictly to the construction herein set forth; but,

35 Having fully described my invention, what I claim as new, and desire to secure by Letters Patent, is—

1. In a truss, the combination, with the supporting-bar, the pad, and means for securing

the pad to the supporting-bar in sliding adjustment toward and away from the bar, of a plate-spring independent of the said means for securing the pad to the bar, said spring being secured to the bar, and having its free end in engagement with the back of the pad, substantially as set forth. 40 45

2. In a truss, the combination, with the supporting-bar, pads secured to the bar, and having sliding adjustments toward and away from the bar, of a single spring secured to the bar 50 between the pads, and having its free ends in contact with the backs of the pads, substantially as set forth.

3. In a truss, the combination, with the supporting-bar, pad, and pad-supporting stud 55 clipped to the bar, of a flat spring clipped to the bar at one side of the stud, the free end of the spring being provided with an elongated slot adapted to embrace the shank of the stud, whereby the pad may be adjusted lengthwise 60 of the supporting-bar without disturbing the spring, substantially as set forth.

4. In a truss, the combination, with the supporting-bar, pad, and pad-supporting stud, the pad being provided with a rounded raised portion around the pad-supporting stud, of a plate-spring clipped to the bar, its free end being slotted to receive the shank of the stud and made concave to conform to the raised portion on the pad, substantially as set forth. 65 70

In testimony whereof I have signed this specification in the presence of two subscribing witnesses.

WM. ELSTUN.
